UNITED STATES PATENT OFFICE.

LEONIDAS SENNETT, OF RUSSELL, KENTUCKY, ASSIGNOR OF ONE-HALF TO JAMES E. RICE, OF RICHMOND, VIRGINIA.

VALVE.

Specification of Letters Patent. Patented Dec. 21, 1915.

1,164,879.

Application filed April 7, 1915. Serial No. 19,806.

To all whom it may concern:

Be it known that I, LEONIDAS SENNETT, a citizen of the United States, residing at Russell, in the county of Greenup and State of Kentucky, have invented a new and useful Valve, of which the following is a specification.

This invention relates to a valve especially designed for use in connection with gas supply systems, one of the objects of the invention being to provide a valve which will close automatically when relieved of the pressure of gas or other fluid thereagainst and which will be locked in closed position so that the same cannot be opened until a key or other device provided for that purpose is utilized.

There are times when the supply of illuminating gas to residences and the like is cut off by accident or intent and, unless the consumers of the gas are notified, the cutting off of the supply will result in the extinguishing of lights with the result that, when the supply of gas is restored, the gas will be free to escape from the open fixtures, with danger of asphyxiating persons unaware of the occurrence.

One of the objects of the present invention is to provide a valve located between the main and the meter in a structure and which valve is held open by pressure but is adapted, when relieved of pressure, to close automatically and to be locked in such position so that when the pressure is restored there will be no danger of gas escaping through open fixtures.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings: Figure 1 is a vertical longitudinal section through the valve casing and showing the valve mechanism therein in elevation, the valve being shown in open position. Fig. 2 is a view similar to Fig. 1 and showing the valve locked in closed position. Fig. 3 is an elevation of

one end of the valve casing. Fig. 4 is a detail view of the valve seat.

Referring to the figures by characters of reference 1 designates a cylindrical casing which can be made of any suitable metal and which is adapted to be placed in the pipe leading from the gas main to the meter in the residence or other structure to be supplied. This casing 1 is preferably interiorly screw threaded at its ends, as shown at 2, one end portion of the casing receiving a disk 3 having a series of openings 4, this disk constituting a valve seat. The disk is likewise provided with a small central guide opening 5 in which is slidably mounted one end portion of a valve stem 6. The other end portion of the valve stem is slidably mounted in a spider 7 which is in engagement with the other threaded end of the casing. A valve 8 is fixedly connected to the stem 6 and may be of any preferred construction, this valve being adapted, when pressed against the seat 3, to close the openings 4. A collar 9 is secured to the stem 6 and a spring 10 is mounted on the stem and bears at one end against the collar and at its other end against the spider, this spring operating to hold the valve 8 pressed toward its seat.

Pivottally mounted upon the spider 7 is a latch lever 11 having a long locking arm 12 and a short arm 13, said short arm having a depending finger 14 provided with an eye 15. Arm 12 is so proportioned that when the valve 8 is pressed against its seat, said arm 12 will fit snugly back of the valve and hold it against movement away from the seat, as shown in Fig. 2. The arm 13 and its finger 14 are so proportioned that when arm 12 is lifted out of engagement with the valve 8, the said finger 14 will be brought to position back of the stem 6 where the eye 15 will be capable of receiving one end of the stem 6, as shown in Fig. 1.

It is to be understood that lever 11 can be actuated in any preferred manner. For example, a key 16 may be mounted for rotation in the wall of casing 1, this key being provided, at its inner end, with a crank arm 17 overhanging the arm 13 of lever 11 and being provided at its outer end with a finger piece 18 of any preferred construction.

It is to be understood that the pressure of gas flowing from the main in the direction of the arrow in Fig. 1 will tend to push the

valve 8 off of its seat 3. By rotating the key 16 so as to force the crank arm 17 downwardly on the arm 13, the long locking arm 12 of lever 11 can be lifted out of position back of the valve 8 and the finger 14 can be lowered into position across the path of the stem 6. As soon as valve 8 is released in this manner, the pressure of the gas thereagainst will force it away from the seat 3 and against the action of spring 10, thus thrusting one end of stem 6 into the eye 15 and locking the lever 11 in set position, as shown in Fig. 1. As long as the pressure within the casing is maintained at or above a predetermined degree, the parts will remain substantially in the positions shown in Fig. 1. If, however, the pressure in the main should fall below a predetermined degree, as when the supply of gas is cut off, the spring 10 would thrust the valve 8 against its seat 3, thus withdrawing the stem 6 from the eye 15 and causing the arm 12 to gravitate to position back of the valve 8 where it will lock the valve against the seat 3. Consequently should the pressure of gas within the main be restored, the passage of the gas through the casing 1 would be prevented until the key 16 should be actuated manually to shift lever 11 and release valve 8 in the manner hereinbefore described. Obviously by the use of a valve such as herein described, the danger of asphyxiation due to the accidental shutting off and restoring of the gas supply, will be eliminated.

35 While the valve herein described is especially useful in connection with gas supply systems, it is to be understood that it can

also be used wherever fluids of any kind are supplied under pressure.

What is claimed is:—

1. A casing having a passage therethrough and with a valve seat intermediate the passage, a valve engaging said seat and adapted to be held open by pressure through the passage, yielding means for automatically closing the valve against its seat when relieved of pressure, a valve stem, a lever engaged by the stem when the valve is open and held thereby out of engagement with the valve, said stem being movable out of engagement 50 with the lever when the valve is closed to release the lever, said lever, when released, constituting means for engaging the valve to hold it on its seat.

2. The combination with a casing, and a 55 valve seat therein, of a valve, a stem movable therewith, means mounted on the stem for holding the valve normally pressed against its seat, said valve being adapted to open under the action of pressure there- 60 against, a locking lever fulcrumed within the casing, an eye movable therewith and adapted to be engaged by the stem when the lever is in set position and the valve is open, and means movably mounted in the casing 65 for engaging the lever to shift it to set position and release the valve.

In testimony that I claim the foregoing as my own, I have hereto affixed my signature in the presence of two witnesses.

LEONIDAS SENNETT.
